DESIGN FOR A WHEEL FOR ARTICLES OF CANE OR RATTAN FURNITURE OR THE LIKE

Robert L. Ficks, Cincinnati, Ohio, assignor to
The Ficks-Reed Company, Cincinnati, Ohio,
a corporation of Ohio

Application April 21, 1937, Serial No. 68,915

Term of patent 7 years

To all whom it may concern:

Be it known that I, Robert L. Ficks, a citizen of the United States, residing at Cincinnati, in the county of Hamilton and State of Ohio, have invented a new, original, and ornamental Design for a Wheel for Articles of Cane or Rattan Furniture or the like, of which the following is a specification, reference being had to the accompanying drawing, forming a part thereof.

Figure 1 represents a side elevation of a wheel showing my new design.

Figure 2 is an edge view of the same, and includes a fragmentary sectional view further illustrating the invention.

In claim:

The ornamental design for a wheel for articles of cane or rattan furniture or the like substantially as shown.

ROBERT L. FICKS.
